UNITED STATES PATENT OFFICE.

WILLIAM A. JOHNSON, OF YONKERS, NEW YORK.

TENNIS-COURT MARKER.

No. 850,936.

Specification of Letters Patent.

Patented April 23, 1907.

Application filed August 9, 1906. Serial No. 329,820.

To all whom it may concern:

Be it known that I, WILLIAM A. JOHNSON, a citizen of the United States, and a resident of the city of Yonkers, in the county of Westchester and State of New York, United States of America, have invented certain new and useful Improvements in Tennis-Court Markers, of which the following is a specification.

10 My invention relates to certain new and useful improvements in tennis-court markers; and its object is to provide a simple and efficient apparatus for marking lines upon a surface, such as a tennis-court, foot-ball field, &c.

15 I will describe my invention in the following specification and point out the novel features thereof in claims.

Referring to the drawings, Figure 1 is a side elevation of my improved marker. Fig. 2 is a sectional front elevation of the same apparatus, the handle being removed and the section being taken through the line 2-2 of Fig. 1. Fig. 3 is a plan view. Fig. 4 is an enlarged sectional side view of the valve mechanism and brush supporting and adjusting parts which are shown in Fig. 1.

Like characters of reference designate corresponding parts in all of the figures.

20 10 designates a tank or receptacle adapted to hold a marking fluid, such as slaked lime. This receptacle is supported by a frame 11, which is mounted upon wheels 12, 12. Each of these wheels is preferably provided with a scraper 13.

25 35 The tank itself may be constructed of any desired material and in any convenient form. I have shown it as a rectangular box of sheet metal. It may be provided with a hinged cover 14. A screen 15 may be placed within

40 the tank supported upon angle-irons 16 near the upper portion of the tank. One or more baffle-plates 17 may be placed within the tank to prevent splashing. A handle 18 of any suitable construction may be attached to 45 one end of the apparatus. In the bottom of the tank is an outlet 20, to which a valve 21 is connected. A flexible tube 22 is connected to the opposite side of this valve.

23 is a lever connected to operate the valve 50 21. This valve-lever is connected with an operating-rod 24, which is carried up to a point near the handle 18, where it may be bent, as shown at 25, to facilitate its manipulation. A fixed stop 26 is provided on the

frame 11 in the path of movement of the 55 valve-lever 23 to limit the movement of the latter lever when it has been pushed over to close the valve 21. An adjustable stop-piece 27 is shown on the other side of valve-lever 23, which is arranged to limit the movement 60 of the lever when it has been pulled over to open the valve 21. Screws 28, extending through a slot in the stop-piece 27 and into the frame 11, are provided for the purpose of setting the stop-piece, and thus adjusting the 65 amount of the maximum opening of the valve 21 to a predetermined degree.

30 designates a bracket which is attached to the lower part of the frame 11 and to which a supporting-arm 32 is pivoted at 31. 70 To the under side of one end of the supporting-arm 32 an ordinary flat paint-brush 33 may be clamped by means of a screw 34. The flexible outlet-tube 22 is led to a point near this end of the supporting-arm and may 75 be attached thereto.

A designates a surface upon which this apparatus is to be used. It may be seen that the brush 33 is arranged to rest upon and to be drawn over this surface. It may be arranged to do this by its own weight. I prefer, however, to provide an arrangement which I will now describe for increasing the pressure of the brush 33 upon the surface A.

80 A tension-spring 36 may be connected to 85 the supporting-arm 32 at the opposite end from that to which the brush is attached. A regulating-screw 37 in the arm 32 may be provided to limit the upward movement of this end of the supporting-arm, and a lock-nut 38 may be used in conjunction with this screw to hold it in place after it has been set in the desired position.

39 designates a guide which I sometimes use to prevent any lateral movement of the 95 supporting-arm 32 and the brush 33.

The operation of this apparatus is obvious. A suitable marking fluid is placed in the tank or receptacle 10. The surface to be marked off may be laid out with strings to act as 100 guides, and the apparatus may be pushed along with its forward wheel following these guide-lines. The valve 21 may be opened by a movement of operating-rod 24, when the marking fluid will pass down through flexible tube 22 to the brush 33, which will 105 spread it upon the surface as desired. The lower part 35 of the end of supporting-arm

32 which holds the brush may be suitably grooved to feed the marking fluid evenly to the brush.

The brush may be of any desired width.

5. The marks which I have according to common practice called "lines" for laying off a lawn-tennis court are two inches in width. A wider or a narrower brush may be used for wider or narrower lines.
10. The scrapers 13 13 will remove particles of dirt from the wheels, and thus prevent the wheels from marking the surface. The front portion of the frame 11 may be made flat, as shown, so that it will catch any foreign matter which is scraped from the front wheel. This is important, as the front wheel is often run directly over old lines in remarking a tennis court.

While means are provided for causing the brush 33 to bear upon the surface to be marked, the flexible outlet-pipe 22 and the spring 36 are so arranged that the brush will be raised by any lumps or projections and will not gouge into a surface such as an athletic field. Another of the many advantages of this device is the ease with which the brush may be removed to be cleansed or to be replaced by another brush. The operator may at will vary the flow of the marking fluid to 25 the brush and may of course shut it off entirely. A hook 40 may be provided to hold the brush off from the ground when the apparatus is not in use or is being moved about over surfaces which are not to be marked.

35. This invention is applicable to many uses other than those herein pointed out, and I do not, of course, limit myself to any specific uses.

What I claim is—

40. 1. A wheeled receptacle adapted to contain marking fluid, and a flexible outlet-pipe connected to said receptacle.
2. A receptacle, a running-gear therefor, a brush and a flexible connection between the receptacle and the brush.
45. 3. A receptacle, a running-gear therefor, a flexible outlet-pipe, a brush associated with said pipe, and means for yieldably adjusting the position of the outlet-pipe and the brush.
50. 4. A wheeled receptacle adapted to be moved across a surface, an outlet-pipe, a brush associated with said pipe, the brush being arranged to bear upon said surface, and means for producing a constant pressure of said brush upon the surface.
55. 5. A receptacle, a running-gear therefor,

an outlet-valve connected with said receptacle, a brush and a hollow flexible connection between the valve and the brush.

6. A wheeled receptacle, a handle therefor, an outlet-valve connected with said receptacle, a brush, a hollow flexible connection between the valve and the brush, and means for operating said valve from the handle.

7. A wheeled receptacle, a handle therefor, an outlet-valve connected with said receptacle, a brush, a hollow flexible connection between the valve and the brush, an operating-rod arranged for operating the valve from the handle, a stop for the valve in its closed position, and an adjustable stop for limiting the amount of opening of the valve.

8. A receptacle, a running-gear therefor, a pivoted supporting-arm and a brush detachably affixed to said arm.

9. A receptacle, a running-gear therefor, a pivoted supporting-arm, a brush detachably affixed to said arm, and a flexible connection between the receptacle and the brush.

10. A receptacle adapted to be moved across a surface, a running-gear therefor, a pivoted supporting-arm, a flat brush detachably affixed to said arm, a flexible connection between the receptacle and the brush, a spring arranged to act upon said supporting-arm to cause the brush to bear upon said surface with a constant pressure, and an adjusting-screw for limiting the action of the spring.

11. A receptacle adapted to contain a marking fluid, a frame, wheels therefor, scrapers for the wheels, a handle, an outlet-valve connected with the receptacle, a pivoted supporting-arm, a brush, means for attaching the brush to the supporting-arm, a hollow flexible connection between the outlet-valve and the brush, a spring arranged to act upon the supporting-arm, an adjusting-screw for limiting the action of the spring, an operating-rod arranged for operating the outlet-valve from the handle, a stop for the valve in its closed position, and an adjustable stop for limiting the amount of opening of the outlet-valve.

In testimony whereof I have signed my name to this specification in the presence of two subscribing witnesses.

WILLIAM A. JOHNSON.
